Primary Examiner—Stella Reid*Assistant Examiner*—Derrick Holland(74) *Attorney, Agent, or Firm*—Fitch, Even, Tabin & Flannery(57) **CLAIM**

The ornamental design for a food package, as shown and described.

DESCRIPTION

FIG. 1 is a perspective view of a food package, showing my new design;

FIG. 2 is a perspective view thereof, in a horizontal orientation;

FIG. 3 is a front elevational view thereof;

FIG. 4 is a top plan view thereof;

FIG. 5 is a bottom plan view thereof;

FIG. 6 is a rear elevational view thereof;

FIG. 7 is a right side elevational view thereof;

FIG. 8 is a left side elevational view thereof; and,

FIG. 9 is an exploded perspective view thereof, showing the lid lifted off the food package.

The broken line portions shown in the food package are for illustrative purposes only and form no part of the claimed design.
